[57] CLAIM

The ornamental design for an applicator, as shown and described.

DESCRIPTION

FIG. 1 is a left side elevational view of an applicator showing our new design;
FIG. 2 is a front elevational view thereof, the rear elevational view being identical;
FIG. 3 is a right side elevational view thereof;
FIG. 4 is a top plan view thereof;
FIG. 5 is a bottom plan view thereof;
FIG. 6 is a top plan view thereof with the cap closure and dauber removed;
FIG. 7 is a left side elevational view of the cap closure and dauber shown separately for clarity of illustration;
FIG. 8 is a front elevational view thereof;
FIG. 9 is a right side elevational view thereof; and,
FIG. 10 is a bottom plan view thereof.
